United States Patent

Des. 239,196

Patented Mar. 16, 1976

239,196

LAMP

James T. Poston, 8109 Clover Way,
Buena Park, Calif. 90620

Filed July 29, 1974, Ser. No. 492,414

Term of patent 14 years

Int. Cl. D26—05

U.S. Cl. D48—20 R

FIG. 1

FIG. 3

FIG. 2

FIG. 4

FIG. 5

FIG. 1 is a perspective view of a lamp showing my new design looking downwardly;

FIG. 2 is a perspective view of the lamp looking upwardly;

FIG. 3 is an elevational view thereof, the glass being shown in broken lines for illustrative purposes only;

FIG. 4 is an enlarged top plan view thereof, the wick assembly being omitted for convenience of illustration;

FIG. 5 is an enlarged bottom plan view thereof.

I claim:

The ornamental design for a lamp, substantially as shown and described.
